Primary Examiner—Susan J. Lucas**Assistant Examiner**—Cynthia Ramirez**[57] CLAIM**

The ornamental design for an ice scraper, as shown and described.

DESCRIPTION

FIG. 1 is a top, front, right perspective view of an ice scraper showing our new design;

FIG. 2 is a top plan view thereof;

FIG. 3 is a front elevational view thereof;

FIG. 4 is a left side elevational view thereof, the right side being a mirror image;

FIG. 5 is a rear elevational view thereof;

FIG. 6 is a bottom plan view thereof; and,

FIG. 7 is a cross-sectional view thereof, taken from line 7—7 of FIG. 1.
